UNITED STATES PATENT OFFICE.

JOHN P. BOYLE AND WALTER A. INMAN, OF CHICAGO, ILLINOIS; SAID INMAN
ASSIGNOR TO SAID BOYLE.

ICE-MANUFACTURING APPARATUS.

1,397,498.

Specification of Letters Patent.

Patented Nov. 22, 1921.

Application filed June 8, 1918. Serial No. 239,009.

To all whom it may concern:

Be it known that we, JOHN P. BOYLE and WALTER A. INMAN, citizens of the United States, residing at Chicago, in the county of Cook and State of Illinois, have invented a certain new and useful Improvement in Ice-Manufacturing Apparatus, of which the following is a full, clear, concise, and exact description, reference being had to the accompanying drawings, forming a part of this specification.

Our invention relates to ice manufacturing apparatus and more particularly to apparatus in which artificial ice is produced simultaneously in a plurality of containers. When ice is thus produced, it is necessary to agitate the water in the container in order to prevent the formation of a visible core in the center of the ice. In order to produce clear ice in these tanks, it is necessary to eliminate the air bubbles or small particles of finely subdivided air found in the water, as otherwise these particles, when the water is frozen, cause the ice to assume a non-transparent appearance, as before outlined.

The preferred form of agitating the water during the freezing process in order to eliminate these small particles of finely subdivided air consists in the introduction of a tube into the water to be frozen, through which tube air is blown. The air blown into the water causes the water to be agitated sufficiently to discharge these air bubbles.

Our invention concerns itself with the provision of means for readily and quickly disconnecting these pipes from a main pipe through which the air is supplied. It must be understood that after the water in the container is entirely frozen, the tubes before mentioned are frozen into the body of the ice. It is then necessary subsequently to heat these tubes in any suitable manner to melt the ice surrounding them so that these tubes can be withdrawn.

We will explain our invention more in detail by referring to the accompanying drawings, in which—

Figure 1 is a fragmentary sectional view of a plant showing a plurality of tanks in which blocks of ice are to be frozen;

Fig. 2 is a top view thereof;

Fig. 3 is a fragmentary side view of one of the tubes shown as connected with the lateral air pipe;

Fig. 4 is a sectional view on line 4—4 of Fig. 3, and

Figs. 5 6 and 7 are views similar to Fig. 4 showing modifications of the connecting structure.

Referring more particularly to Fig. 1, we show a main refrigerating chamber 10 within which is provided a compartment 11 formed by the walls 12. In the compartment 11 we provide a plurality of supports 13 upon each of which a tank 14 is mounted. These tanks 14 are filled with water which is to be frozen into blocks of ice. Suitable spacers 15 are provided to assist in alining the tanks 14. There is also provided a main air supply pipe 16 which feeds a plurality of lateral air supply pipes 17, 17. The lateral air supply pipes 17 are then associated with the depending tubes 18 so that the air from the main supply pipe 16 is blown through the tubes 18 into the liquid into which these tubes 18 project. The laterals 17 are preferably connected with the main supply pipe 16 through the interposition of suitable couplings 19 and valves 20.

Our invention concerns itself with the provision of means whereby to provide a simple, efficient, easily connectible and disconnectible association between the laterals 17 and their coöperating tubes 18. The improved connection which we have provided will be more clearly apparent from an inspection of Figs. 3 and 4. As more clearly shown in these figures, the tubes 18 are open at their lower extremities and are also provided with small openings 21 near their lower ends.

In accordance with our invention the laterals 17 are provided with nipples 22 which are preferably screw threaded into position, these nipples preferably having shoulders 23 so they may serve to hold spring fingers 24 in position. The nipples 22 have discharge openings 25, as shown, so that the air may blow therethrough into the tubes 18. The tubes 18 preferably have connecting sleeves 26 attached to their upper extremities, which connecting sleeves have seats at their upper extremities so that they may seat against the lower surfaces of the nipples in an airtight manner. The sleeves 26 also have beveled extremities, as shown more clearly at 27, to coöperate with the spring fingers 24.

From the construction thus described it will be readily seen that if the tubes 18 were

frozen in the ice that all that would be necessary to disconnect the lateral 17 would be to exert sufficient force to lift the lateral 17 away from its connected tubes 18, the force required being merely sufficient to disengage the spring fingers 24 from their hold against the beveled surfaces of the sleeves 26. The fingers 24 are of course strong enough to hold the tubes 18 normally so that the connection between the sleeves 26 and the nipples 22 is substantially airtight.

By referring to Fig. 1, it will be readily seen in how simple a manner the laterals 17 may be removed after the water in the tanks 14 has been frozen and the tubes 18 are held tightly by the ice. All that it is necessary to do is to disconnect the lateral 17 from the main supply pipe 16 by disconnecting the coupling 19, whereupon this lateral may be lifted off from its position, leaving the tubes 18 behind. The tanks 14 may then be removed and the tubes 18, when properly warmed, taken out of their positions within the blocks of ice.

In Fig. 5, we show a modified form of the structure illustrated in Fig. 4, in that the nipple 22 in addition to holding the spring fingers 24 in position, also holds a rubber or similar gasket 28 in position. The sleeve 26^a is not provided with a seat to engage the nipple 22, but directly abuts the gasket 28, thus again forming a substantially airtight connection.

In Fig. 6, we show a further modified form in which the exposed portions of the nipples 22 take the form of truncated cones, the sleeves 26^b having an internal shape to conform thereto so as to provide a substantially airtight connection.

Fig. 7 shows a further modification wherein the spring fingers 24^c are secured directly to the laterals 17 by means of the screws 30.

In showing the modifications of Figs. 5, 6 and 7, we do not wish it to be understood that these are the only modifications available, as many modifications may be made within the spirit of our invention without departing from its scope.

Having however thus described certain forms which our invention may take, what we claim as new and desire to secure by Letters Patent is:

1. Ice manufacturing apparatus of the character described comprising a rigid substantially horizontally extending air supply pipe, a plurality of rigid substantially vertically extending tubes depending therefrom, and yieldable spring fingers carried by the pipe for rigidly joining the tubes to the pipe so that the pipe may be simultaneously disconnected from all of said tubes, after which said tubes may be removed from the ice by a substantially vertical movement thereof.

2. A device of the character described comprising an air supply pipe, nipples formed thereon, tubes adapted to seat, at one end, against said nipples, and spring fingers carried by said pipe for holding the tubes in substantial air tight connection with said nipples.

3. Ice manufacturing apparatus of the character described comprising an air supply pipe, a depending tube, a sleeve carried by the tube and having beveled shoulders formed at its lower end, and spring fingers carried by the pipe for engaging the beveled shoulders on said sleeve for detachably connecting the tube to the pipe.

4. In ice manufacturing apparatus of the character wherein blow tubes are positioned within ice forming containers and are adapted to be frozen into the ice, the combination of an air supply pipe, nipples formed thereon, tubes having beveled shoulders formed thereon and spring clips carried by the pipe for holding said tubes in contact with said nipples but permitting the pipe to be simultaneously disconnected from all of said tubes when they are frozen in.

5. In ice manufacturing apparatus of the character wherein blow tubes are positioned within ice forming containers and are adapted to be frozen into the ice, the combination of an air supply pipe, nipples formed thereon, blow tubes depending from said pipe, sleeves attached to the upper extremities of the tubes and having seats formed at their upper extremities to engage said nipples and means carried by the pipe for holding said sleeves in contact with said nipples but permitting the pipe to be disconnected simultaneously from all said sleeves when said tubes are frozen into the ice formed in said containers.

6. Ice manufacturing apparatus of the character described comprising a rigid tubular horizontal distributing member, rigid vertical tubes and means carried by said horizontal member for rigidly coupling said tubes thereto, said means providing readily detachable connections whereby said pipe will be simultaneously disconnected from all of said tubes by a slight vertical movement thereof.

7. Ice manufacturing apparatus of the character described comprising a rigid tubular horizontal distributing member, rigid vertical tubes and resilient means carried by said horizontal member for rigidly coupling said tubes thereto, said means providing readily detachable connections whereby said pipe will be simultaneously disconnected from all of said tubes by a slight vertical movement thereof.

8. Ice manufacturing apparatus of the character described comprising a rigid tubular horizontal distributing member, rigid vertical tubes, and means carried by said

horizontal member for rigidly coupling said tubes thereto, said means providing readily detachable connections adapted to withstand air under pressure whereby said member will be simultaneously disconnected from all of said tubes by a slight vertical movement thereof.

9. Ice manufacturing apparatus of the character described comprising a rigid tubular horizontal distributing member, rigid vertical tubes, and means carried by said

horizontal member for rigidly clamping said tubes thereto, said means providing readily detachable connections adapted to withstand air under pressure whereby said member will be simultaneously disconnected from all of said tubes by a slight vertical movement thereof.

In witness whereof we hereunto subscribe our names this 27th day of May, A. D. 1918.

JOHN P. BOYLE.

WALTER A. INMAN.
